UNITED STATES PATENT OFFICE

ROBERT T. DAWES, OF HUDSON, MASSACHUSETTS

GUY ROPE

Application filed October 29, 1931. Serial No. 571,770.

This invention relates to an improvement in ropes of the kind having a loop of readily adjustable length at one end, such ropes being especially useful as braces or guys for 5 masts, awnings, tents or the like as well as for slings, binding bands, or other constrictive purposes and in accordance with this invention the rope embodies integral securing means by which the loop may be adjusted 10 to any desired length and automatically held in such condition. When such ropes are to be used in exposed situations, for example as tent ropes or on board ship, I contemplate, in accordance with this invention, the impregnation of the rope with some suitable 15 protective substance.

As is well known, a guy rope is usually fastened at one end to the mast, tent or the 20 like to be braced or secured in place and the free end is looped around a stake or other fixed object, which end, after the rope has been made taut, is fastened to the main length of the rope. When the free end is 25 knotted to the main length it has been found difficult to prevent a certain amount of slippage or to increase or decrease the tension 30 of the rope as when any variance therein takes place due to changes of heat or moisture. It has heretofore been suggested that 35 buckles, cleats or similar fastening means be employed, but such means are not entirely reliable and increase the cost since, due to the ordinary exposure of the rope to all kinds 40 of weather conditions, any such means of metal must be rust-proofed or made of bronze or other rust-resistant material.

The guy rope embodying my invention, 45 however, avoids the above mentioned objections, entirely eliminates the use of buckles, cleats or other supplementary fastening means, is easy to use, quickly released or secured, and when the rope is taut it will be held automatically in such condition.

In the accompanying drawing:

Fig. 1 illustrates the guy rope in its normal tensed condition;

Fig. 2 illustrates one way of loosening the 50 tension of the rope;

Fig. 3 illustrates one way of increasing the tension of the rope;

Fig. 4 illustrates a tent provided with guy ropes made in accordance with my invention; 55 and

Fig. 5 is a fragmentary side elevation, to large scale, showing the rope as impregnated with a suitable protective substance.

In Fig. 4 is shown a tent 10 secured by 60 guy ropes 11 to tent stakes 12. The guy rope 11 is attached at the end 15 to the body of the tent and has a free end 16 which after being looped around the tent stake is secured to the main length 17 of the rope by means 65 about to be described.

The rope here illustrated is braided as indicated in Figs. 1, 2 and 3 and the length 70 17 is provided with a longitudinally disposed sleeve portion 20 which is preferably integral with the length 17. The sleeve 20 is arranged to lie lengthwise between the free 75 ends of the guy rope and is proportioned to receive the free end 16 to form a loop which may extend about or be secured to a fixed anchoring member such as the stake 12. In order that this sleeve may function as means 80 for automatically gripping and retaining the free end 16 of the guy rope, as well as to be capable of releasing this portion when desired—thereby to permit adjustment of the 85 loop and the effective length of the rope—the sleeve is preferably in the form of a tubular member which may be made of helically disposed strands so arranged that the body portion of the sleeve is capable of elongation or stretching when placed under tension, as when the guy rope is drawn taut 90 between the stake 12 and its end 15. This elongation of the sleeve is effective to reduce its cross-sectional area and thereby to cause it to contract about that portion of the end 16 disposed therein so as to bind and to grip 95 securely this portion of the rope. A tubular braid may be cited as an instance of a sleeve member having inherent characteristics as just described.

Since the sleeve 20 possesses a certain amount of elasticity, when the length 17 is under tension the walls of the sleeve will con- 100

tract around the free end 16 and prevent any shift of its position in the sleeve. When, however, it is desired to move the free end 16, this can readily be done by relieving the 5 length 17 of tension. In Fig. 2 is shown one way to loosen the guy rope, the length 17 being held adjacent the end 21 of the sleeve and the free end 16 being drawn in the direction indicated by the arrows. Fig. 3 similarly illustrates one manner of manipulating the guy rope to increase its tension the length 10 17 being grasped near the end 22 of the sleeve and the free end being drawn through the sleeve in the direction indicated by the 15 arrows.

It will be noted that the free end 16 is automatically secured against movement in the sleeve 20 and that in order to move the free end 16 through the sleeve 20 in either direction the length 17 must be grasped adjacent the opening from which the end is to pass out of the sleeve.

As it would otherwise be possible to pull the cord too far to the right, as shown in 25 Fig. 2, in which case the end of the cord might be removed from the sleeve, or the free end of the cord might be drawn within the free end of the sleeve far enough to be inaccessible, it is advisable to form an obstruction or abutment of some kind for limiting movement of the flexible member through the sleeve. To this end an enlargement or knot 18 may be formed in the portion 16 and to such size as to be effective to prevent movement into the sleeve.

Braided material such as here described is particularly advantageous for tent ropes, since the braided structure is neutral as respects twist, and thus does not kink or snarl 40 easily. Moreover, such braided material of the requisite strength may readily be made from cotton yarns, and this is highly advantageous from the military standpoint, since cotton is a product of this country, whereas 45 most of the other rope fibers must be imported from foreign sources. However, in order to prevent deterioration of the rope, especially when made of cotton fiber, I contemplate impregnating or coating it with some suitable protective substance. Thus, I find that 50 aluminum acetate is a good impregnant for combatting mold, mildew, and the depredations of insects, but for certain purposes I may prefer oily, waxy, or bituminous impregnants, rubber latex, pyroxylene or similar cellulose derivatives, phenol condensation products, or the like, which furnish good 55 protection against climatic conditions.

I claim:

60 1. An adjustable guy rope comprising an elongate braided cord having a flexible free end, and a sleeve integral with said elongate member and spaced from said free end, said sleeve being constructed and arranged so that 65 said free end may be inserted longitudinally

through said sleeve and project outwardly toward the opposite end of said cord thereby to form a loop, said sleeve being capable of stretching longitudinally and of contracting transversely about and thereby gripping the 70 free end of said elongate member disposed therein when said member is subjected to longitudinal tension, said sleeve being retractile longitudinally at will to cause it to expand transversely thereby releasing the free end of the elongate member and permitting longitudinal movement thereof through the sleeve when said tension is released, whereby the effective length of the guy rope and size of said loop may be adjusted as desired. 75

2. An adjustable guy rope comprising an elongate member having a flexible free end, and a stretchable and contractile tubular sleeve spaced from said free end, said free 80 end being bent upon itself to form a loop with said free end extending longitudinally through and projecting beyond the sleeve, said projecting free end constituting means for shortening the effective length of the guy 85 rope and size of the loop, said sleeve being capable of stretching longitudinally and of contracting transversely, thereby gripping that portion of the free end disposed therein when subjected to longitudinal tension, said 90 sleeve being contractile longitudinally at will to cause it to expand transversely when said longitudinal tension is released, thereby releasing said portion of the free end and permitting longitudinal movement thereof through the sleeve, whereby the effective 95 length of the guy rope and size of the loop may be adjusted as desired. 100

3. An adjustable guy rope comprising an elongate braided cotton cord impregnated with a preservative substance and having a flexible free end, a stretchable and contractile tubular sleeve integral with said cord and spaced from said free end, said sleeve being constructed and arranged so that the free end of the cord may be inserted longitudinally therethrough and project outwardly toward the opposite end of said cord thereby to form a loop, said sleeve being capable of stretching longitudinally and of contracting transversely about and thereby gripping that portion of the free end disposed therein when subjected to longitudinal tension, said sleeve being retractile longitudinally at will to cause it to expand transversely and thereby to release said portion of the free end and thus permit longitudinal movement of said free end through the sleeve to vary the effective length of the guy rope and size of the loop, and an enlargement formed in said free end for limiting the movement thereof through the sleeve in the direction from the enlargement toward the sleeve. 110 115

4. A guy rope for tents comprising an elongate member having one end adapted to 120 125

be permanently attached to a tent and also having a flexible free end, and a tubular sleeve integral with said member and spaced from said free end, said member with its
5 sleeve consisting of braided textile strand material impregnated with a protective substance, said flexible free end being bent upon itself to form a loop with its free end extending longitudinally through and projecting
10 outwardly beyond the sleeve, the projecting end constituting means for shortening the length of the loop, said sleeve being capable of stretching longitudinally and of contracting transversely thereby gripping that portion
15 of the free end disposed therein when subjected to longitudinal tension, said sleeve being retractile longitudinally at will to cause it to expand transversely when said longitudinal tension is released, thereby releasing said portion of the free end and permitting longitudinal movement thereof through the sleeve, whereby the effective length of the guy rope and size of the loop may be adjusted as desired.

25 Signed by me at Boston, Massachusetts, this 27th day of October, 1931.

ROBERT T. DAWES.
